CLAIM

The ornamental design for a hot beverage server, substantially as shown and described.

DESCRIPTION

FIG. 1 is a front perspective view of a hot beverage server showing my new design;

FIG. 2 is a front elevational view;

FIG. 3 is a right side elevational view;

FIG. 4 is a left side elevational view;

FIG. 5 is a top plan view;

FIG. 6 is a front perspective view of a hot beverage server showing a modified form of the new design wherein a top plate has been removed;

FIG. 7 is a front elevational view;

FIG. 8 is a right side elevational view;

FIG. 9 is a left side elevational view; and

FIG. 10 is a top plan view.

The undisclosed bottom of the hot beverage server is conventional in appearance.
